UNITED STATES PATENT OFFICE.

JAY M. JOHNSON, OF CHICAGO, ILLINOIS, ASSIGNOR TO WILLIAM P. BUTLER, OF BERWYN, ILLINOIS.

TICKET MUTILATING, CANCELING, AND COUNTING DEVICE.

1,270,837.

Specification of Letters Patent.

Patented July 2, 1918.

Application filed January 19, 1916. Serial No. 72,924.

To all whom it may concern:

Be it known that I, JAY M. JOHNSON, a citizen of the United States, and a resident of the city of Chicago, in the county of Cook

5 and State of Illinois, have invented certain new and useful Improvements in Ticket Mutilating, Canceling, and Counting Devices; and I do hereby declare that the following is a full, clear, and exact description of the 10 same, reference being had to the accompanying drawings, and to the numerals of reference marked thereon, which form a part of this specification.

This invention relates to a mechanism 15 forming a part of a ticket and fare collecting box which operates to receive tickets deposited therein, canceling and mutilating the same, as well as counting the number of tickets handled by the machine.

20 It is an object therefore of this invention to construct a mechanism adapted to receive a ticket inserted thereinto acting to deface or cancel, as well as mutilate the ticket, and operating also to count the number of tickets 25 defaced or canceled.

It is also an object of this invention to 30 construct a mechanism one member of which operates continuously and acts together with another member normally at rest to receive a ticket therebetween to mutilate and deface the same, thereby bringing said second member into driving operation to drive a registering mechanism to count the tickets.

It is also an object of this invention to 35 construct a ticket canceling and mutilating mechanism wherein one of the elements thereof is caused to move first by engagement with the ticket which also engages a constantly driven element, and thereafter 40 said first element, by the interlocking of a clutch, completing its movement after discharge of the ticket to effect registration of the ticket.

45 It is furthermore an important object of this invention to construct a pair of co-acting rolls adapted to receive a ticket inserted therebetween, one of said rolls driven continuously and the other normally disconnected from a constantly driven clutch, said 50 rolls provided with defacing and mutilating means whereby when a ticket is inserted therebetween the normally stationary roll is caused to rotate, thereby causing engagement of the clutch and completion of the 55 rotation of the normally stationary roller

thereby, and with a register connected to the shaft to the normally stationary element to effect registration of the ticket received through said rolls.

It is finally an object of this invention to 60 construct an improved power driven mechanism to pass a ticket between mutilating and defacing rolls and effect registration of the ticket.

The invention (in a preferred form) is 65 illustrated in the drawings and hereinafter more fully described.

In the drawings:

Figure 1 is a front elevation of a fare register equipped with a ticket receiving, 70 mutilating, defacing and registering mechanism embodying my invention.

Fig. 2 is a side view thereof.

Fig. 3 is a top plan view of the ticket handling mechanisms, shown detached from 75 the fare box.

Fig. 4 is a fragmentary detail view taken on line 4-4 of Fig. 3, with parts shown in section and parts in elevation.

Fig. 5 is a rear elevation of the rolls taken 80 on line 5-5 of Fig. 3.

Fig. 6 is a similar view, but with the parts broken away and shown in section.

Fig. 7 is a detail view with parts in section and parts in elevation taken on line 85 7-7 of Fig. 6.

Fig. 8 is a detail section with parts in elevation taken on line 8-8 of Fig. 6.

Fig. 9 is a detail sectional view with parts omitted and parts in elevation, taken on line 90 9-9 of Fig. 5.

Fig. 10 is a sectional detail taken on line 10-10 of Fig. 5.

As shown in the drawings:

As shown in Figs. 1 and 2, a fare box or 95 register, denoted as a whole by the reference numeral 1, has a ticket collection box, denoted as a whole by the reference numeral 2, forming an extension on the forward or front end thereof. An extension 3, projects 100 on one side of the ticket extension 2, and visible through a slot in said extension are the numerals on the dials of a register or counter 4. As clearly shown in Fig. 1, a slot 5, is provided in the front wall of said extension 2, to permit insertion of tickets therethrough and the tickets so inserted into the machine are received between the defacing and mutilating devices hereinafter described.

For this purpose, attached upon the frame plates 5 and 6, of the extension 2, of the fare box, are plates 7 and 8, respectively, of the frame of the ticket handling mechanism. 5 Integral with or attached to said respective frame plates 7 and 8, are supports or extensions 10 and 11, respectively, there being one of the former and two of the latter, by which frame plate members 12 and 13, 10 respectively are held disposed in parallel relation between the respective frame plates 7 and 8. Journaled between and supported by said inner frame plates 12 and 13, is an electric motor 14, of any suitable type, the 15 shaft of which is provided with a worm 15. Journaled between the frame plates 7 and 13, in bearings 16, formed integral with the plate 13, is a short shaft 17, having secured on one end thereof a worm wheel 18, meshing with said worm 15, and at its other end provided with a small bevel pinion 19. Also journaled between the respective inner frame plates 12 and 13, are hollow cylindrical rolls 20 and 21, respectively, the upper roll 20, 25 of which is at one end provided with a shaft extension on which is secured a bevel pinion 22, meshing with the bevel pinion 19. A closure member 23, is threaded into the open end of each of the respective rolls 20 and 21, whereby an inking or defacing fluid may 30 be introduced therein, after which, of course, said closure members are replaced to seal the same.

Radial passages 24, are provided in each 35 of the respective cylindrical members 20 and 21, and surrounding the same are absorbent marking bands or rings 25, the bands of the lower roll contacting those of the upper roll so as to mark and ink lines on a ticket passed 40 therebetween as said rolls are rotated. Also mounted upon each of said respective rolls 20 and 21, are toothed cutting knives 26, three on each of said rolls, with the cutting knives on the lower roll 21, of slightly less 45 diameter and offset slightly, as clearly shown in Figs. 5 and 6, from the cutting knives on the roll 20, so that a scissors cutting effect is gained by the co-action of said knives when the same are rotated.

50 Mounted adjacent the two outermost cutter knives 26, on the upper roll 20, are guard or stripper fingers 27, which are loosely journaled upon the roll 20, so as not to rotate therewith. Similarly mounted adjacent the 55 outermost cutter knives 26, of the lower roll 21, are guard or stripper fingers or members 28, also journaled upon a roll 21, so as not to rotate therewith. The purpose of said stripper members 27 and 28, is to prevent a ticket 60 which is passing between the co-acting cutting knives from adhering thereto and rotating around therewith. Spacer washers or collars 29, are mounted on each of said rolls 20 and 21, between the respective cutters 65 26, and inking bands 25, to hold and

maintain the same properly disposed upon the rolls.

Rigidly mounted on the ends of the roll 20, is a pinion or gear 30, with a spacing sleeve 31, disposed between the same and 70 the inner end cutter 26, on said roll, and a collar 32, is threaded on said roll 20, to hold the gear and said associated spacer sleeve, washer, cutter knives and the inking band, clamped thereon. Rotatably sleeved near 75 one end of the roll 21, upon a spacer sleeve 33, is a toothed clutch element 34, and rigidly associated therewith is a pinion or gear 35, which meshes with said pinion 30. A nut or collar 36, is threaded on the roll 21, 80 to hold said spacer sleeve 33, in position thereon and to also maintain the cutter knives and inking bands properly disposed.

Also sleeved upon the rollers 21, though keyed thereto in any suitable manner to 85 cause rotation therewith, is a clutch element 37, which is normally impelled by means of a coiled spring 38, into engagement with the clutch element 34, whereby the roll 21, is driven from the roll 20, through 90 the gears 30 and 35. However, said clutch element 37, is normally held retracted from the constantly driven clutch member 34, and for this purpose a retaining finger 39, is mounted upon a rod 40, secured between said 95 plates 12 and 13, and the lower edge thereof which projects beneath the roll 21, and is provided with an inclined face 41, as clearly shown in Figs. 5 and 9. Mounted upon the sleeve clutch element 37, is a pin 42, which, 100 as said clutch element 37, rotates around, strikes against the inclined surface 41, of said retaining finger, so that the clutch element is thereby retracted and held against the compression of its spring, with the roll 105 21, at rest. The stripper fingers 28, of the lower roll 21, project downwardly and engage over the transverse rod 40, and are held from rotation thereby with the roller 21.

Means are also provided for preventing 110 overtravel of the roll 21, or in other words limiting the rotation thereof to one revolution for each ticket passed into the machine, and for this purpose a notched disk 43, is secured on and near one end of said roll adjacent the frame plate 13, and is adapted to be engaged by a spring impelled detent comprising an arm 44, pivotally mounted on the frame plate 13, and provided with a roller 45, for engagement in the notch of 115 120 the disk 43, and normally impelled toward the same by a spring 46.

Mechanism is also provided for imparting a drive to the register 4, from the roll 21, and for this purpose a shaft extension 125 47, is formed on one end of said roll 21, passing through the plate 13, and plates 7 and 9, into the registering casing 3, where suitable mechanisms of a well known type are provided to drive the register dials. 130

The operation is as follows:

The tickets for collection and registration are inserted through the slot 5, of the fare box extension 2, whereupon the constantly rotating roll 20, driven from the motor 14, wedges the forward edge of the ticket between the cutting knives 26, and inking bands 25, of said respective rolls 20 and 21, so that due to the engagement of 10 said ticket with said elements, rotation is imparted to the roll 21. This rotation continues for a short time sufficient for the pin 42, on the clutch element 37, of the roll 21, to pass beyond the upper end of the retaining finger 39, whereupon the clutch element 37, springs into engagement with the clutch element 34, so that the roll 21, is caused to rotate positively through the small pinions 30 and 35, until the pin 42, rotates 20 around to strike against the inclined edge 41, of said retaining fingers to thereby again retract the clutch element 37, and disconnect the drive from the roll 21. Overtravel of the roll 21, is prevented by the notched disk 25 43, and spring impelled detent arm 44, so that only one complete revolution of said roll 21, takes place and a corresponding movement of the register dials in the register 4, to count one ticket. The co-acting 30 cutting knives 26, of said respective rolls act to mutilate the ticket, and the inking bands 25, serve to mark ink lines on each surface thereof, so that the canceled and mutilated ticket, although readable, cannot 35 be used fraudulently if, for any reason, it is obtained from within the collecting compartment of the fare box. In order to replenish the marking fluid within the respective rolls 20 and 21, it is only necessary to 40 unscrew the closures 23, thereof. The guards 27 and 28, on the upper and lower rolls respectively, serve effectually to prevent the tickets clinging to the rolls after passage therethrough, so that the tickets are stripped 45 therefrom and fall into the collecting compartment of the fare box.

I am aware that various details of construction may be varied through a wide range without departing from the principles 50 of this invention, and I therefore do not purpose limiting the patent granted otherwise than necessitated by the prior art.

I claim as my invention:

1. In a machine of the class described, co-acting rolls, mechanisms mounted thereon to cut through a ticket and simultaneously place a defacing mark on the surface thereof as it is passed between said rolls, means for constantly driving one roller, and a mechanism controlled by the tickets for driving the other roller from the constantly driven roller when the tickets are inserted in the machine.

2. In a device of the class described, a pair 65 of inking rollers adapted to ink a ticket

passing therebetween, mutilating wheels on said rollers, intermeshing gears on said rollers, one rigidly secured to its roller and the other loose on its roller, a clutch mechanism on one roller, mechanism for releasing the 70 same when a ticket is inserted between the rollers whereby the clutch mechanism rotates the roller from the loose gear.

3. In a device of the class described, a pair of inking rollers adapted to ink a ticket 75 passing therebetween, mutilating wheels on said rollers, intermeshing gears on said rollers, one rigidly secured to its roller and the other loose on its roller, a clutch mechanism on one roller, mechanism for releasing the 80 same when a ticket is inserted between the rollers whereby the clutch mechanism rotates the roller from the loose gear, mechanism for limiting the roller with the loose gear to one revolution for each ticket, and 85 mechanism for disengaging the clutch from the loose gear for each revolution of the roller.

4. In a device of the class described, co-acting rolls, means of one character thereon 90 cutting, and means of another character thereon defacing a ticket passed therebetween, a register for registering the number of tickets operated upon, and mechanism set in operation by insertion of a ticket for 95 automatically actuating the register to count each ticket inserted between the rollers.

5. In a collecting machine of the class described, co-acting rolls, mechanisms mounted thereon to cut through the ticket and simultaneously place a defacing mark on the surface thereof, registering means for registering the number of tickets collected and a mechanism controlled entirely by the 100 tickets for automatically actuating the register for each ticket fed to the rollers.

6. In a collecting machine of the class described, mechanisms adapted to receive a ticket to mutilate and deface the same, and means connected to said mechanisms and caused to operate by the insertion of a ticket 110 for registering the number of tickets collected.

7. In a machine of the class described, co-acting mechanisms adapted to receive a 115 ticket therebetween to move the same therethrough, devices forming a part of said mechanisms to cut and deface the ticket passed therethrough, and a register connected to said mechanisms and automatically caused to operate due to insertion of a ticket into said mechanisms for registering the 120 number of tickets collected.

8. In a collecting machine of the class described, co-acting rolls, inking devices associated therewith to deface the surfaces of a ticket passed therebetween, cutting mechanisms associated with said rolls to mutilate a ticket passed therebetween, a register mechanism connected for operation by one of 125 130

- 4
- said rolls to count the number of tickets collected, a clutch on one roll adapted to drive the same from the other roll, and mechanism for disengaging the clutch for each revolution of the roll. 5
9. In a device of the class described, co-acting means to mutilate and deface a ticket, mechanisms constantly driving one of said means, and a clutch device for connecting the other of said means to said first mentioned means to be driven thereby, by the initial movement imparted to said second mentioned means by insertion of a ticket between said co-acting means. 10
15. 10. In a machine of the class described, co-acting mutilating and defacing means for a ticket, mechanism driving one of said means, a clutch device for effecting driving connection between the second of said means and said first mentioned means when a ticket is inserted thereinto, and means to limit the rotation of said second means to one revolution for each ticket inserted into the machine. 20
25. 11. In a machine of the class described, co-acting mutilating and defacing means for a ticket, mechanism driving one of said means, a clutch device for effecting driving connection between the second of said means and said first mentioned means when a ticket is inserted thereinto, means to limit the rotation of said second means to one revolution for each ticket inserted into the machine, and a register for registering the number of tickets operated upon. 30
35. 12. In a device of the class described, co-acting mutilating and defacing means for a ticket, one of said means continuously driven, a clutch associated with the other of said means whereby with said clutch disengaged the other of said means is normally at rest, means retaining said clutch in disengaged position to permit said clutch to be released by slight rotation of said second mentioned means due to insertion of a ticket between said co-acting means, mechanism for limiting the rotation of said second mentioned means to one revolution for each operation of said co-acting means, and a counter connected to said second mentioned means to count the revolutions thereof and thereby register the number of tickets collected. 45
50. 13. In a device of the class described, co-acting devices to mutilate and deface a ticket, a power drive therefor normally driving one of said means, mechanisms acting automatically to connect the second of said
- means to the driven means when a ticket is passed through said co-acting means, and a register for counting the revolutions of said second mentioned means. 60
14. In a device of the class described, a register and a ticket canceling device normally out of operative relation with the register and adapted by insertion of a ticket to be adjusted into operative relation with the register to register the ticket thereon. 65
15. In a device of the class described, a mutilating and canceling member, a register, a mutilating and canceling member connected to operate the register and means controlled by the insertion of a ticket for driving one of the canceling members from the other. 70
16. In a device of the class described, a ticket register, a power driven ticket canceling device and mechanism automatically operated by the insertion of a ticket for driving the register from the ticket canceling device. 75
17. In a device of the class described, a motor, a canceling roller driven thereby, a canceling roller coacting therewith and inoperative except upon insertion of a ticket, 80 a register connected to operate with the second named canceling roller and a mechanism controlled by the insertion of the ticket for operating the canceling rollers together. 90
18. In a device of the class described, an automatically operated canceling device operated by insertion of tickets and a register device automatically operated by insertion of tickets to count the number of tickets canceled. 95
19. In a device of the class described, a ticket register, a ticket canceling device and mechanism controlled by the tickets for automatically operating both the ticket register and canceling device. 100
20. In a device of the class described, ticket canceling members, a clutch member for connecting the same to operate together, a mechanism operated by insertion of a ticket for adjusting the clutch into operative position and a ticket registering device connected to be operated from the canceling device. 105
